UNITED STATES PATENT OFFICE

159,150

TEXTILE FABRIC

Julian B. Gregg, North Bergen, N. J., assignor to Chicopee Manufacturing Corporation of Georgia, a corporation of Georgia

Application March 30, 1950, Serial No. 8,863

Term of patent 14 years

(Cl. D92—1)

To all whom it may concern:

Be it known that I, Julian B. Gregg, a citizen of the United States, residing at North Bergen, in the county of Hudson, State of New Jersey, have invented a new, original, and ornamental Design for a Textile Fabric, of which the following is a specification, reference being had to the accompanying drawing, which drawing is a plan view of a fabric showing my new design.

I claim:

The ornamental design for a textile fabric, as shown.

JULIAN B. GREGG.
